UNITED STATES PATENT OFFICE.

WILLIAM A. PARSONS, OF MILWAUKEE, WISCONSIN.

PARQUET FLOORING.

Application filed November 17, 1921. Serial No. 515,750.

To all whom it may concern:

Be it known that I, WILLIAM A. PARSONS, a citizen of the United States, and resident of Milwaukee, in the county of Milwaukee and State of Wisconsin, have invented certain new and useful Improvements in Parquet Flooring; and I do hereby declare that the following is a full, clear, and exact description thereof.

10 My invention is a parquet flooring. It contemplates the utilization of blocks which may be made from waste material in a structure wherein a plurality of the blocks are united by a longitudinal tongue extending 15 through grooves.

When a number of these blocks are assembled and the tongue is inserted to unite them, they are used as a unit in a larger structure. A series of these units are assembled and locked together by suitable tongue and groove connection, and long transverse and longitudinal members are utilized to form a firm and stable flooring, the transverse and longitudinal members 25 being suitably secured to the series of units. The blocks are sawed cross-grained so as to create a stronger structure.

Other advantages and objects of my invention will appear as the description proceeds.

Reference is had to,

Figure 1, wherein a plan view is shown of a portion of flooring.

Figure 2 is a cross section on the line 35 2-2 of Figure 1.

Figure 3 is a perspective of a unit, and

Figure 4 is a bottom view of an alternative modification.

Figure 5 shows a cross sectional detail. 40 Unit 10 consists of a series of similar shaped blocks, three in number, which are grooved to receive pigeon-tail 12, which extends the entire length of the three blocks and unites them rigidly together. A tongue 5 13 is provided on one side and a groove 14 on the other.

Figure 2 illustrates the manner of assembly of the units. A unit 11 is immediately contiguous to units 10 which are adjacent to each other. Unit 11 is provided

with two grooves 15 on opposite sides. Transverse members 16 are provided with tongues 17 for engagement in the grooves in the units. Longitudinal members 17 extend across transverse member 16 being grooved 55 to receive a portion of transverse member 16, as shown at 18 and in Figure 5.

The precise form of pigeon-tail 12 illustrated is not necessary in my invention.

If desired, the units may be connected by 60 a cylindrical rod, block being bored to receive same.

As shown, pigeon-tail 12 projects below the bottom of the block in order to space it properly from the floor, as is apparent in 65 Figure 2. This prevents the accumulation of moisture beneath the blocks and eliminates all tendency to warp.

If desired, suitable tongue and groove 70 connection may be made between the longitudinal members 17 and the series of blocks.

In the modification shown in Figure 4, six blocks are used to each unit instead of the three shown in Figure 3.

From the assembly of the unit shown in 75 Figure 3, a square formation, as shown in Figure 1, results. The result of the assembly of the modification, shown in Figure 4, is substantially similar.

As the length of a block 18' is twice its 80 width, the unit shown in Figure 4 has the same dimensions as that shown in Figure 3.

In all modifications of the device, the blocks are sawed cross grained so as to create a strong structure, the flooring thus 85 revealing the grain of the wood cut across.

I claim:

A parquet flooring comprising a plurality of blocks, each having a groove directed upwardly from its bottom surface, and 90 a pigeon-tail fitting into said groove and holding said blocks together, said pigeon-tail extending below the bottom of said blocks.

In testimony that I claim the foregoing 95 I have hereunto set my hand at Milwaukee, in the county of Milwaukee and State of Wisconsin.

WILLIAM A. PARSONS.
